corporation of Delaware

Application September 6, 1939, Serial No. 293,551

3 Claims. (Cl. 210—70)

5 The present invention pertains to the art of centrifugal separators designed to effect dehydration of solids, and periodic removal of dehydrated solids from the centrifugal rotor by the action of a dislodging tool or knife which is intermittently moved into position to perform its dislodging function after accumulation of the layer of dehydrated solids in the centrifugal rotor.

10 The invention was conceived as an improvement in the means designed to actuate the dislodging tool of the centrifugal separator described and claimed in my co-pending application Serial No. 170,246, filed October 21, 1937. In the machine of that application, the dehydration of solids was accomplished in an automatic centrifugal machine which operates through definite cycles comprising passage of slurry to the centrifugal rotor, centrifugally separating liquid

15 from solids, rinsing and drying the separated solids, and unloading the separated solids, the unloading operation being started while the drying operation is still in progress with respect to part of the solids in the centrifugal rotor.

20 The present invention is concerned solely with the means for actuating the dislodging tool, and may be used in connection with the machine of my prior application, identified above, or with other machines in which the dislodging tool is periodically moved into the body of solids which has accumulated in the rotor during the dehydrating operation.

25 The object of the invention has been to provide a simple and positive means for actuating the dislodging tool, entailing a minimum of vibration, and ensuring positive and steady dislodging operation.

30 Other objects of the invention will be evident from a reading of the following specification in the light of the attached drawings, in which,

35 Figure 1 is a front elevation of the machine of the invention,

40 Figure 2 is a central axial cross section of the machine of Figure 1,

45 Figure 3 is a detailed cross section on the line 3—3 of Figure 2, and

50 Figure 4 is a diagrammatic view illustrating the resolution of forces occurring in the action of the dislodging tool of the invention.

55 Referring to the drawings by reference characters, the illustrated machine comprises a frame 10, which is provided with spaced bearings, of which only one, the bearing 11 is illustrated. A shaft 12 is mounted for rotation in these bearings and is driven by any suitable source of

power (not shown) in the direction indicated by the arrow A in Figure 1.

The machine is provided with a centrifugal rotor 13 (Fig. 2), which comprises a wall 14, which may be cylindrical as shown, a ring 15 extending inwardly from one end of said wall and provided with an opening 16 and an end wall 17 which is fixedly mounted upon the shaft 12, as by being keyed thereto.

A housing 18, which encloses the rotor, is mounted upon the frame 10, and comprises an end wall 19, a circumferential wall 20 and an end plate or closure member 21 which, preferably, is detachably secured to the circumferential wall 20. This housing is provided with an outlet 22 for discharging liquid which is separated from solids in the rotor during the operation of the machine.

The wall 14 of the rotor is provided, around its inner circumference, with filter means in the form of a screen 23, which lies snugly within said wall. The screen may be a single ply, woven screen fitted under pressure within the wall 14, and may comprise closely spaced continuous circumferential strands and widely spaced, axially extending strands, as described and claimed in my co-pending application Serial No. 170,246, referred to above.

A discharge chute 24 extends from the exterior of the rotor through the opening 16, and the upper end of said discharge chute is positioned to receive solids dislodged from the screen 23 by a dislodging tool 25, which is intermittently moved into position adjacent the screen to effect removal of solids from that screen. The dislodging tool 25 is provided with a cutting edge or knife 26 (Fig. 3) adjacent its leading edge, and is also provided with a deflecting surface 27 adapted to direct solids dislodged by the cutting edge 26 into the upper end of the discharge chute 24.

The dislodging tool is connected by arms 28 and 29 to a shaft 30 which extends axially of the rotor. This shaft 30 is preferably rectangular in cross section, and may be mounted for longitudinal adjustment in a boss 31. The boss 31 is in turn secured to an arm 32, which is pivotally secured to a fixed part of the machine, and thus serves to pivot about the point 31 as a fulcrum. A link 33 is also pivotally secured to the boss 31 and to a piston rod 34 which is connected to a piston 35 which is operated within a cylinder 36. The prime mover 35—36 may be actuated by any suitable form of fluid pressure, e. g., by oil or steam.

The operation of the machine will now be apparent. After a mass of slurry has been fed to the machine and substantially completely dehydrated in accordance with the normal operation 5 of the machine, including rinsing and drying cycles if desired, hydraulic fluid is admitted to the lower side of the piston 35 to effect movement of the dislodging tool 25 into the bed of solids which has accumulated within the screen 23. The 10 movement of the piston 35 upwardly pulls the boss 31 and shaft 30 upwardly, and causes the arm 32 to move pivotally about the fulcrum 37. This pivotal movement of the shaft 30, attached arms 28 and 29, and dislodging tool 25, brings 15 the dislodging tool into cutting contact with the bed of dehydrated solids (e. g., crystals), and gradually effects discharge of these solids into the chute 24 and from the machine. It will be understood that the cutting action of the dislodging tool 25 is progressive, this dislodging tool moving gradually more deeply into the bed of solids as the dislodging action progresses.

An important feature of the invention consists 20 in the relation between the fulcrum point 37, the angle taken by the cutting edge or knife 26 relatively to the solids being dislodged, and the weight of the sum of the parts consisting of the piston 35, piston rod 34, link 33, boss 31, shaft 30, arms 28 and 29, and dislodging tool 25. An important advantage is obtained in the practice of 25 the invention by correlating these factors in such a way that, of the force V acting upon the dislodging tool because of impingement of solids thereagainst and the vertical downward force W 30 acting on that tool because of the weights of the aforementioned parts associated therewith, the resultant R is in direction below the fulcrum point 37. The desirability of this feature consists in the fact that, if the resultant of these 35 forces were to act to pull arm 32 upwardly instead of downwardly, the forces in question would act to augment the force imposed on the underside of the piston 35 by fluid pressure, and to exercise sudden, variable, and uncontrollable 40 effects on the dislodging tool in impelling it more deeply into the bed of solids. By correlating the above-mentioned factors in such a manner that the resultant of the forces described 45 above acts against the normal lifting force of the fluid pressure on the under side of the piston 35, this undesired effect of causing the knife 26 to gouge too deeply and irregularly into the bed of solids is avoided, and vibration is also minimized. The resolution of forces referred to above 50 is illustrated by the force diagram of Figure 4 55 of the drawings.

Modifications will be obvious to those skilled in the art, and I do not wish to be limited except 60 by the scope of the subjoined claims.

I. claim:

1. In a centrifugal separator, the combination comprising, a centrifugal rotor, means for rotating said rotor to effect dehydration of solids fed thereto and accumulation of a bed of dehydrated solids within said rotor, a dislodging tool mounted within said rotor for movement into and away from solids dislodging position alternately, and means for moving said dislodging tool to and from solids dislodging position, said last-named means comprising, a shaft secured to said dislodging tool, said shaft extending to the exterior of said rotor, a pivoted arm secured to said shaft, and mounted for movement with said shaft to control the movement of said shaft about the fulcrum of said pivoted arm, and fluid pressure means secured to said shaft and adapted to effect movement of said shaft alternately toward the circumferential wall of the rotor and away from the circumferential wall of the rotor. 20

2. In a centrifugal separator, the combination comprising, a centrifugal rotor, means for rotating said rotor to effect dehydration of solids fed thereto and accumulation of a bed of dehydrated solids within said rotor, a dislodging tool mounted within said rotor for movement into and away from solids dislodging position alternately, and means for moving said dislodging tool to and from solids dislodging position, said last-named means comprising, a pivoted arm 25 mounted outside of said rotor and secured to said dislodging tool to control the movement of said tool about the fulcrum of said pivoted arm, and fluid pressure means also secured to said dislodging tool and adapted to effect movement of said dislodging tool alternately toward the circumferential wall of the rotor and away from the circumferential wall of the rotor. 35

3. In a centrifugal separator, the combination comprising, a centrifugal rotor, means for rotating said rotor to effect dehydration of solids fed thereto and accumulation of a bed of dehydrated solids within said rotor, a dislodging tool mounted within said rotor for movement into and away from solids dislodging position alternately, and means for moving said dislodging tool to and from solids dislodging position, said last-named means comprising, a shaft secured to said dislodging tool, said shaft extending to the exterior of said rotor, a pivoted arm 45 secured to said shaft, and mounted for movement with said shaft to control the movement of said shaft about the fulcrum of said pivoted arm, a link secured to said shaft, a piston rod secured to said link, and a reciprocating fluid 50 pressure motor associated with said piston rod to effect movement of said shaft alternately toward the circumferential wall of the rotor and away from the circumferential wall of the rotor. 55
